UNITED STATES PATENT OFFICE

HARCOURT C. DRAKE, OF HEMPSTEAD, NEW YORK, ASSIGNOR, BY MESNE ASSIGNMENTS, TO SPERRY PRODUCTS, INC., OF BROOKLYN, NEW YORK, A CORPORATION OF NEW YORK

RAIL FISSURE DETECTOR

Application filed March 18, 1930. Serial No. 436,660.

This invention relates to improvements in rail fissure detectors of the type adapted to be mounted on a moving car. The fact that the detector is continuously moved over the rails creates a multiplicity of problems which it is the purpose of this invention to solve.

More specifically it is one object of this invention to insure operation of the paint gun which is employed for marking the spot on a rail where a fissure occurs. It has been found in practice that the very short energization of the detecting mechanism caused by the relatively rapid movement of the detector mechanism over a fissure was sometimes insufficient to actuate the paint gun operating mechanism. By my invention such operation is insured.

It is a further object of my invention to provide means for preventing operation of the paint gun when the detector mechanism passes over the rail joints. I accomplish this function without preventing actuation of the usual recorder on the recording chart for indicating rail joints. For this purpose I employ a mechanical means designed to engage the angle bar which connects the rails at the joints. I provide means also for insuring that the paint gun will not be operated until the recording mechanism has passed completely beyond the said angle bar.

In the Sperry detector mechanism, to which this invention applies, current of very high amperage is led into the rail and passes out of said rail at a point removed from the point of entrance. In order to insure good contact of the contact brushes, said brushes have been pivotally mounted in the supporting carriage and spring pressure has been applied to them. It has been found, however, that when the spring pressure is increased substantially it tends to lift the brushes off the rail and so defeat the purpose for which the spring pressure was intended. It is an object of my invention, therefore, to provide auxiliary means for holding the brushes in firm contact with the rail. This means may take the form of hydraulic or air pressure means designed to be applied to the brush holders for holding

the brushes in firm contact with the rail. Such pressure may act against the action of strong springs, such as have heretofore been used. The pressure may be applied by a double acting engine so that said pressure may be utilized for raising the brushes off the rail as well as moving them into contact therewith.

It has been found further that in order to build up magnetic flux around the rail a sufficient time must be allowed for the current to pass into the rail. I, therefore, provide for spacing the contact brushes adequately so that the time of passage of the current from the inlet brushes to the outlet brushes will be sufficient to permit a magnetic flux to be built up around the rail. Further, I position the detector brushes a distance further removed from the inlet brushes than from the outlet brushes.

Heretofore the paint gun has been mounted on the car body and this has resulted in the "wiping off" of the gun by obstructions in the path of travel of the car. By my invention I propose to mount the paint gun on the contact brush holder which is lifted to a protected inoperative position when obstructions are met.

It is a further object of my invention to mount the paint gun sufficiently behind the detector brushes to compensate for the speed of the car and the time lag of the paint gun operating mechanism.

Still another object of my invention is to mount the detector sled on the brush holder by means which will permit a universal movement of the sled within a limited range so that the sled may align itself with the rail head and maintain a position parallel to the rail head surface.

It is a further object of this invention to mount the detector sled on means such as grooved rollers which will provide spaced contact edges or skis, both of which constructions permit the sled to maintain contact with the rail head in spite of irregularities in the surface to a greater degree than was possible heretofore with the ordinary type of rollers.

A further object of this invention is to

mount the detector coils in such manner that the distance of said coils with respect to the rail head surface will be substantially constant. For this purpose I propose a pivotal 5 mounting of the detector coils in the detector sled.

Still another object of this invention is the provision of means for effecting quick contact engagement of the current conducting 10 brushes when it is desired to make a hand test of a portion of the rail in which a flaw is suspected.

Further objects and advantages of this invention will be apparent in the following 15 detailed description:

In the accompanying drawings,

Fig. 1 is a side elevation of a Sperry detector car, showing generally the location of the principal elements of the detector mechanism. 20

Fig. 2 is an enlarged detail, partly sectioned vertically, of a portion of the contact brush holder and detector mechanism.

Fig. 3 is an enlarged detailed view of the 25 detector sled disclosing its universal mounting.

Fig. 4 is a section taken substantially on the line 4—4 of Fig. 3.

Fig. 5 is a view similar to Fig. 4 disclosing 30 a modified form of roller.

Fig. 6 is a detailed view of the detector sled showing a modified form of mounting the detector coils.

Fig. 7 is a diagrammatic view disclosing 35 the means for preventing operation of the paint gun when the detector mechanism passes over rail joints.

Fig. 8 is a view, largely diagrammatic, disclosing the means for effecting a rapid 40 engagement of the current supply contacts for hand testing.

Fig. 9 is an enlarged detail of a hand clamp for effecting engagement of one current supply contact of Fig. 8 with the rail.

Fig. 10 is a view, sectioned vertically, disclosing a modified form of means for causing 45 the detector coils to maintain a fixed relationship with respect to the rail head surface.

Fig. 11 is a view similar to Fig. 10 of still 50 another modified form of device for effecting the same purpose.

Fig. 12 is an enlarged side elevation of the 55 form of device disclosed in Fig. 6.

Referring to Fig. 1, there is shown a Sperry rail detector car 10 having a contact brush carriage or holder 11 and a detector sled 12 supported on said holder 11. The contact brushes 13—14 carried by the contact brush 60 holder 11 are designed to lead high amperage current into the rail and the coils in the detector sled are designed to pick up any variations in flux caused by flaws and transmit the same through an amplifier to a recording 65 mechanism as disclosed in the patent of El-

mer A. Sperry, No. 1,820,505, granted August 25, 1931. The amplifying means is also designed to energize a mechanism for operating a paint gun 15 for squirting paint upon the rail at the point where a flaw or fissure 70 is detected by the detector mechanism. To insure operation of the paint gun 15 when passing over a rail flaw or fissure, regardless of the speed of the car or the smallness of the flaw, I provide the mechanism disclosed in 75 Fig. 7. The normal paint gun operating mechanism is shown as comprising an electro-magnet 20 energized from the amplifying system, said magnet attracting its armature 21 to close a set of contacts 22, thus energizing electro-magnet 23 which attracts its armature 24 to actuate a recording pen. The closing of contacts 22 also energizes electro-magnet 25 which attracts its armature 26 to close the circuit through electro-magnet 27, 80 which then attracts its armature 28 to close contacts 29. This permits full voltage from a main supply source of 110 volts to be applied to an electro-magnet 30 which attracts its armature 31 to operate a valve 32 to permit 85 air pressure to pass into pipe 33 and discharge paint from gun 15 on the track.

In order to insure operation of the paint gun when passing over a flaw, I provide an additional winding 25' which is energized 90 at the same time as winding 25. When the detector mechanism has passed over the flaw and contacts 22 open to deenergize coil 25, coil 25' will still be energized because it will be seen that it has an independent circuit extending through armature 26, contacts 26' and the conductor 50 to the negative side of the line. Once coils 25 and 25' are energized, therefore, coil 25' will hold the armature 26 to maintain the circuit through coils 27 and 30 until armature 28 has been fully drawn 100 down to open contacts 29' and thus break the circuit through electro-magnet 25'. The full movement of armature 28, however, insures the operation of the paint gun. 110

Referring to the same Fig. 7, I have disclosed also a means for preventing operation of the said paint gun 15 when the detector mechanism passes over a rail joint, since obviously magnetic flux variation, due to a rail joint, would tend to operate the paint gun operating mechanism in the same manner as a flaw or fissure within the rail. For this purpose I provide a mechanically pivoted lever 40 so supported as to engage the angle bar at the side of the rail and connecting the two rails at the joint. As lever 40 engages the angle bar it closes a set of contacts 41 to energize coils 42 and 43 to open contacts 44 and close contacts 45. The opening of contacts 44 prevents energization of electro-magnet 25 and 25' and hence of the circuit through magnet 27 and magnet 30, while the closing of contacts 45 closes the circuit through electro-magnet 51 to actuate the armature 52 120

which operates the joint recording pen on the chart. The opening of contacts 44 serves also to break the circuit through coil 23 so that the fissure-recording pen will not be actuated when the detector passes over a rail joint.

Since the lever 40 would normally disengage the angle bar before the detector sled has passed beyond the rail joint, I provide a second lever 40' so positioned with respect to lever 40 that it will engage the angle bar before lever 40 has left the bar to close a set of contacts 41' in parallel with contacts 41 to perform the same function and continue the action of contacts 41 in preventing operation of the paint gun 15 until the detector sled has passed entirely beyond the rail joint.

Referring to Fig. 2, I have shown the contact brush holder 11 and the brushes 13 which are in the form of pivoted levers 55 whose upper ends are spring-pressed by springs 56 to cause the brushes 13 to engage the rail head surface firmly. The pressure necessary to insure firm contact of the contacts 13 was found to be sufficient to lift the entire contact brush holder off the rail. I, therefore, provide positively actuated means for maintaining the contact brush holder in lowered position and the current supply contacts 13 in firm engagement with the rail. Such means may take the form of an air cylinder 60 in which operates a piston 61 having a rod 62 pivotally connected to the brush contact holder at 63. Air or fluid pressure may be employed to force the piston downwardly when it is desired to lower the contact brush holder into engagement with the rails and to maintain the contacts firmly in engagement with the rails. If desired, the cylinder 60 may be a two-way cylinder so that fluid pressure may be used not merely to lower the contact brush holder but also to raise the same to inoperative position. I provide further means whereby the said fluid-operated piston may be controlled either from the driver's compartment or from the operator's compartment. For this purpose I have shown an electrically operated air valve 65 with switches 66 and 66' located in the driver's and operator's compartments respectively, said switches having parallel connection to the electrically operated air valve.

It has been found that a certain interval of time is necessary in order to build up the magnetic flux around the rail. I have found that this result can be effected by spacing the current supply contact brushes 13 and 14 a substantial distance and then positioning the detector sled further removed from the front or inlet supply brushes and nearer the rear brushes 14.

This positioning of the detector sled, relative to the sets of current supply brushes, is essential in any case regardless of the distance between the sets of brushes. This rela-

tive positioning of the detector sled 12 with respect to current supply brushes 13-14 is disclosed in Fig. 1.

Referring to Fig. 2 it will be observed that I have mounted the paint gun 15 on the contact brush holder 11 so that it will be raised and lowered together with said holder. Heretofore the paint gun was mounted on the car body and was frequently wiped off by obstructions at the side of the path of travel of the car. By the construction shown in Fig. 2, this is impossible and the paint gun is at all times maintained in a safe position.

Referring to the same Fig. 2, it will be observed that the paint gun 15 is mounted a certain distance behind the detector sled 12. This distance is so proportioned that the speed of the car and the lag in operation of the paint gun operating mechanism will be compensated for by the distance which the paint gun 15 must travel before reaching the flaw picked up by the sled 12.

The detector sled should maintain its parallelism with the surface of the rail head if the indications or variations in magnetic flux are to be reliable. Since, however, the rail head surface is of varying contour, I provide for corresponding variations of the sled 12 as the detector mechanism passes over the rail. The detector coils are shown at 12' fixed to a carriage 70 which is mounted in a support 71, all of which elements together constitute the sled 12. The support 70 is mounted on means such as rollers 72 in Fig. 3 or skis 74 in Fig. 2, and instead of mounting said support rigidly in the carriage 71, I provide a joint which allows universal movement within predetermined limits so that the support 70 can freely take up the position corresponding to the contour of the rail head at every point as the car proceeds. This mounting may include stems 75 carried by support 70 and extending freely through bushings 76 in the support 71, said stems carrying bolts 77 at their upper ends. Springs 78 normally maintain the support 70 spaced from carriage 71, but it will be seen that this mounting permits universal movement within certain prescribed limits.

The support 70 of Fig. 3 may be provided with rollers 79 as shown in Fig. 4, or more preferably with grooved rollers, such as 80, having two spaced supporting edges 81-82 so that the wheel 80 may accommodate itself more readily to the varying contour of the rail head surface.

If desired, I may replace the rollers 79-80 by skis 74 of Fig. 2 which will also accommodate themselves freely to the varying contours of the rail head surface.

For insuring the maintenance of a fixed distance between the detector coils and the rail head surface regardless of the contour of said surface, I may utilize the form of invention disclosed in Fig. 6 wherein the

detector coils 12" are carried at the ends of levers 83 pivoted on the carriage 85. The levers are spring pressed into engagement with the rail surface by springs 86 and will 5 obviously move about their pivots as the surface of the rail head varies. This form of mounting is disclosed in larger view in Fig. 12.

In Fig. 10, I have shown still another 10 mounting for the detector coils to insure a constant distance between the coil and the surface of the rail head. In this form a block 90 is pivoted at 91 on the ends of lever arms similar to arms 83 and in said block are independently supported rollers 92 and the detector coil 12".

In Fig. 11 there is shown still another modified form for performing the same function as the Fig. 10 device, but in this case the 20 detector coil 12" surrounds the shaft 94 which rotates with the rollers 95, the whole system being supported in a pivoted member 90'.

In Fig. 8, I have disclosed a means whereby 25 I am enabled to effect a rapid attachment of current supply contacts to the rail head when it is desired to make a hand test for flaws. The two contact members are shown at 13'-14', the former being directly beneath 30 the car while the latter is usually some distance therefrom. The contact 13' may be moved downwardly into engagement with the rail head surface by means of an air cylinder 95 controlled from within the car by a 35 valve handle 96, the piston within the cylinder 95 having a piston rod 96' attached to the block 13'. The contact 14' may be in the form of a hook 97 which is designed to be anchored over the rail head as shown in Fig. 40 9 by means of a handle 98 and a second hook 99, pivoted on the fixed frame, is designed to be, swung beneath the rail head when the handle 98 is moved up to vertical position by 45 means of a cam 100 which engages one side of the hook lever 99.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the 50 various features and elements in the combination and relations described, some of these may be altered and others omitted without interfering with the more general results outlined, and the invention extends to such 55 use.

Having described my invention, what I claim and desire to secure by Letters Patent is:

1. In combination, a means adapted to 60 move over the rails for detecting rail flaws,

said means including means for passing current through the rail, a carriage adapted to engage the rail, a detector coil supported by said carriage adjacent the rail, and a support for said carriage including a universal 70 mounting.

2. In combination, a means adapted to move over the rails for detecting rail flaws, said means including means for passing current through the rail, a carriage adapted to 75 engage the rail, a detector coil supported by said carriage adjacent the rail, and a support for said carriage including a resilient universal mounting permitting universal movement to a limited degree.

3. In combination, a means adapted to move over the rails for detecting rail flaws, said means including means for passing current through the rail, a carriage having skis adapted to engage the rail, a detector coil supported by 80 said carriage adjacent the rail, and a support for said carriage including a universal mounting.

4. In combination, a means adapted to move over the rails for detecting rail flaws, 90 said means including means for passing current through the rail, a carriage adapted to engage the rail, a detector coil supported by said carriage adjacent the rail, and a support for 95 said carriage, said carriage being pivotally mounted in said support whereby said detector coil is maintained in fixed relation with the rail head surface.

5. In combination, a means adapted to move over the rails, said means including an 100 electric current generator, brushes adapted to engage the rails for supplying current thereto and detecting means out of contact with the rail for detecting variations in the flux around the rail, said detecting means being spaced sufficiently from said inlet current brushes to permit the molecules of the rail to align themselves for proper polarity.

6. In combination, a means adapted to move over the rails for detecting rail flaws, 110 said means including an electric current generator, front and rear brushes through which the current is adapted to enter and leave respectively, said brushes being adapted to engage the rail, and detecting means 115 out of contact with the rail for detecting variations in the magnetic flux around the rail, said last-named means being positioned nearer the rear brushes than the front brushes to permit the molecules of the rail 120 to align themselves for proper polarity.

7. In combination, a means adapted to move over the rails for detecting rail flaws, 125 said means including an electric current generator, front and rear brushes through which the current is adapted to enter and leave respectively, said brushes being adapted to engage the rail, and detecting means out of contact with the rail for detecting variations in the magnetic flux around the rail, said last 130

named means being positioned adjacent the rear brushes and removed from the front brushes a distance sufficient to permit the molecules of the rail to align themselves for proper polarity.

8. In combination, means adapted to move over the rails for detecting rail flaws, said means including an electric current generator, a current brush carriage adapted to engage the rail to lead current into and out of the rail, a detector carriage adapted to engage the rail and supporting a detector mechanism out of contact with the rail, and means whereby said detector carriage is mounted for movement independent of said current brush carriage.

9. In combination, means adapted to move over the rails for detecting rail flaws, said means including an electric current generator, a current brush carriage adapted to engage the rail to lead current into and out of the rail, a detector carriage adapted to engage the rail and supporting a detector mechanism out of contact with the rail, and means whereby said detector carriage is mounted on said current brush carriage for movement independent thereof.

10. In combination, means adapted to move over the rails for detecting rail flaws, said means including an electric current generator, a current brush carriage adapted to engage the rail to lead current into and out of the rail, a detector carriage adapted to engage the rail and supporting a detector mechanism out of contact with the rail, and means whereby said detector carriage is mounted on said current brush carriage for universal movement independent thereof.

11. In combination, means adapted to move over the rails for detecting rail flaws, said means including an electric current generator, a current brush carriage adapted to engage the rail to lead current into and out of the rail, a plurality of detector coils, and means whereby said coils are supported for independent movement on said carriage.

12. In combination, means adapted to move over the rails for detecting rail flaws, said means including an electric current generator, a current brush carriage adapted to engage the rail to lead current into and out of the rail, a plurality of detector coils, and means whereby said coils are supported for independent movement on said carriage, each of said coils having means adapted to engage the rail to maintain the axis of the coil a constant distance above the rail surface.

13. In combination, means adapted to move over the rails for detecting rail flaws, said means including an electric current generator, a current brush carriage adapted to engage the rail to lead current into and out of the rail, a plurality of detector coils, and means whereby said coils are supported on said carriage for independent movement,

each of said coils having a roller adapted to engage the rail whereby the axis of the coil is moved relative to said carriage to maintain a constant distance above the rail surface.

70

14. In combination, means adapted to move over the rails for detecting rail flaws, said means including an electric current generator, a current brush carriage adapted to engage the rail to lead current into and out of the rail, a detector carriage comprising a plurality of detector coils mounted thereon for independent movement, each of said coils having means adapted to engage the rail to maintain the axis of the coil a constant distance above the rail surface, and means whereby said detector carriage is mounted on said current brush carriage for independent universal movement.

75

In testimony whereof I have affixed my signature.
